Primary Examiner — Selina Sikder*(74) Attorney, Agent, or Firm* — Finnegan, Henderson, Farabow, Garrett & Dunner, LLP(57) **CLAIM**

The ornamental design for an electronic drum module, as shown and described.

DESCRIPTION

FIG. 1 is a front top right perspective view of the electronic drum module showing our new design;

FIG. 2 is a front left bottom perspective view thereof;

FIG. 3 is a front elevation view thereof;

FIG. 4 is a rear elevation view thereof;

FIG. 5 is a left side view thereof;

FIG. 6 is a right side view thereof;

FIG. 7 is a top plan view thereof; and,

FIG. 8 is a bottom plan view thereof.

The broken lines illustrate portions of the electronic drum module that form no part of the claimed design.
